(57) **CLAIM**

The ornamental design for a side table as shown and described.

DESCRIPTION

FIG. 1 is a top, front and right side perspective view for a first embodiment of a side table showing my new design; FIG. 2 is a left side view thereof, a right side view being a mirror image;

FIG. 3 is a front view thereof, a rear view being a mirror image;

FIG. 4 is a top plan view thereof;

FIG. 5 is a bottom plan view thereof;

FIG. 6 is a top, front and right side perspective view for a second embodiment of a side table. The left side and right side views are identical to FIG. 2;

FIG. 7 is a top, front and right side perspective view for a third embodiment of a side table. The left side and right side views are identical to FIG. 2;

FIG. 8 is a top, front and right side perspective view for a fourth embodiment of a side table, shown with a woodgrain surface pattern;

FIG. 9 is a left side view thereof, with the right side view being a mirror image;

FIG. 10 is a front view thereof, with the rear view being a mirror image;

FIG. 11 is a top plan view thereof;

FIG. 12 is a bottom plan view thereof;

FIG. 13 is a top, front and right side perspective view for a fifth embodiment of a side table, shown with a woodgrain surface pattern. The left side and right side views are identical to FIG. 9; and,

FIG. 14 is a top, front and right side perspective view for a sixth embodiment of a side table, shown with a woodgrain surface pattern. The left side and right side views are identical to FIG. 9.

The broken lines illustrate portions of the side table that form no part of the claimed design.
